C. E. TOWNSEND.
POCKET TOOTHBRUSH AND DENTIFRICE HOLDER.
APPLICATION FILED DEC. 29, 1919.

1,343,240.

Patented June 15, 1920.

UNITED STATES PATENT OFFICE.

CHARLES EARLE TOWNSEND, OF NORFOLK, VIRGINIA.

POCKET TOOTHBRUSH AND DENTIFRICE HOLDER.

1,343,240.

Specification of Letters Patent. Patented June 15, 1920.

Application filed December 29, 1919. Serial No. 348,052.

To all whom it may concern:

Be it known that I, CHARLES EARLE TOWNSEND, a citizen of the United States, residing at Norfolk, in the county of Norfolk and State of Virginia, have invented 5 certain new and useful Improvements in Pocket Toothbrush and Dentifrice Holders, of which the following is a specification.

My invention relates to pocket toothbrush 10 and dentifrice holders. The object of the invention is to provide a convenient and sanitary holder for tooth brushes and tooth paste in such a form as to resemble a fountain pen which may be carried in the pocket.

15 The device is very desirable, more particularly for travelers and takes up little room in the pocket.

Further objects and advantages will be 20 more fully described herein and specifically pointed out in the annexed claims recourse being had to the accompanying drawing forming a part of this specification in which:—

Figure 1 is a sectional elevation of my 25 pocket tooth brush and dentifrice holder.

Fig. 2 is a plan of the same.

Fig. 3 is a sectional view of a modification 30 of my device for simply holding the brush and dentifrice without the attachments shown in Fig. 1.

Fig. 4 is a cross section taken on the line 1—2 in Fig. 1, viewed from the position indicated by the arrow.

Fig. 5 is an elevation of the collapsible 35 tube compressing spring detached from the tube, and Fig. 6 is an elevation of the flat tube for ejecting the tooth paste as shown in Fig. 1.

In the drawing like reference numerals 40 indicate similar parts in all the several views.

1 is the main hollow cylindrical portion which forms a handle for the hereinafter described tooth brush of which it forms a 45 part.

The part 1 is provided with a screw cap 2 for removing and replacing a tube of tooth paste; also the tapered portions 1^a for frictionally securing the brush inclosing 50 tube or cylinder 3 thereto.

5 is the shank of the tooth brush and 6 are its bristles.

The flattened shank 5 is produced by the reduction of the thickness of the sloping

part 4 from a circular cross section in order 55 to secure the bristles therein.

The handle portion 1 is provided with a slot 7 for the passage of the pin to which the knob or button 8 is attached.

The button shank is connected to a curved 60 spring 9 having a right angled end 10 and a curved or hooked end 11 for overlapping and holding the collapsible dentifrice tube 12 in place and for slidably moving the same to the right and left for compressing 65 the tube for ejecting the dentifrice and to enable the tube to be withdrawn in order to insert a full one.

As shown, the portion 10 of the spring, when pushed to the right, will squeeze the 70 paste out of the tube in addition to the side pressure exerted by the said spring.

As all collapsible tubes are provided with a threaded outlet 13 for a cover or cap, this is taken advantage of by providing a 75 modified cap 14 to which is attached a flat tube 15 having a bevel end 16, (Fig. 6), by which the tooth paste may be discharged on top of the bristles 6, as shown by the dotted lines 18 in Fig. 1.

The movement of the tube 12 to the right by means of the button 8, will cause the flat tube 15 to pass through the rectangular orifice 17 in the sloping part 4 of the brush handle directly over the brush and a downward pressure, as well as a right hand movement, will eject the dentifrice upon the bristles.

Where the tube manipulating devices already described are not desirable, I arrange 90 the dentifrice tube 12 as shown in Fig. 3, the handle 1 of the brush then simply becomes a receptacle for the tube and the threaded end of which is secured by screwing it into a corresponding female thread 95 in the central portion of the cap 19 and closes its outlet, as shown in Fig. 3.

20 are air vents in the brush inclosing tube so that air may be admitted for circulation to evaporate residual moisture.

The dotted lines in Fig. 1 show the tube drawn backward or toward the left and also show an approximate depression of the spring 9 when compressing the tube 12.

As collapsible tubes are made of very soft 105 metal it will adjust itself so as to permit the flat tube 15 to enter the orifice 17 readily and to return without difficulty.

By my invention I am enabled to produce an attractive, serviceable and sanitary device at a reasonable cost at the same time being very convenient and of a small size so as to be conveniently carried in the pocket in the manner of an ordinary fountain pen.

I claim:

1. A device of the class described and in combination with a tooth brush, of a hollow handle therefor, a compressible tube secured therein and adapted to be removed and replaced at will, a flat tube extension screwed to the outlet of the said compressible tube, and a curved leaf spring operative from the outside of the hollow handle and adapted to compress the compressible tube to eject its contents over the bristles of the brush.
- 10
- 15

2. A device of the class described and in combination with a tooth brush, of a hollow handle therefor, a compressible tube therein, compressing and reciprocating means for said tube, a flat extension tube connected thereto and adapted to be extended over the bristles of the brush, and means for operating said compressing and reciprocating means from the exterior of said hollow handle for ejecting the contents of the tube upon the brush.

In testimony whereof I have hereunto affixed my signature in the presence of two witnesses.

CHARLES EARLE TOWNSEND.

Witnesses:

M. PRIVOTT,
WALTER B. BURROW.
